Primary Examiner — Holly Bayham*Assistant Examiner* — Rhea Shields(74) *Attorney, Agent, or Firm* — Sutherland Asbil & Brennan LLP(57) **CLAIM**

The ornamental design for the container with spout, as shown and described.

DESCRIPTION

FIG. 1 is a perspective view of a first embodiment of a Container with Spout, showing our new design.

FIG. 2 is a front side elevational view thereof;

FIG. 3 is a side elevational view thereof, the other side being a mirror image thereof;

FIG. 4 is a back side elevational view thereof;

FIG. 5 is a bottom view thereof; and

FIG. 6 is top view thereof.

FIG. 7 is a perspective view of a second embodiment of a Container with Spout, showing our new design.

FIG. 8 is a front side elevational view thereof;

FIG. 9 is a side elevational view thereof, the other side being a mirror image thereof;

FIG. 10 is a back side elevational view thereof;

FIG. 11 is a bottom view thereof; and,

FIG. 12 is top view thereof.

The broken lines are directed to environment and show unclaimed subject matter; the broken lines form no part of the claimed design.

1 Claim, 6 Drawing Sheets(56)
